UNITED STATES PATENT OFFICE.

MILTON ALDEN, OF SPRINGFIELD, MASSACHUSETTS, ASSIGNOR TO ALDEN MANUFACTURING COMPANY, OF SPRINGFIELD, MASSACHUSETTS, A CORPORATION OF MASSACHUSETTS.

DESIGN FOR AN ESCUTCHEON PLATE FOR RADIORECEIVERS OR THE LIKE.

Application filed December 3, 1926. Serial No. 19,917. Term of patent 7 years.

To all whom it may concern:

Be it known that I, MILTON ALDEN, a citizen of the United States, residing in Springfield, Hampden County, Massachusetts, have invented a new, original, and ornamental Design for an Escutcheon Plate, for Radioreceivers or the like, of which the following

plate for radio receivers embodying my design.

Fig. 2 is an edge view of the same. The dotted lines show in what connection applicant's escutcheon plate is used.

I claim:

The ornamental design for an escutcheon plate for radioreceivers or the like substantially as shown.

Fig. 1 is a front view of an escutcheon

MILTON ALDEN.
